(57) **CLAIM**

The ornamental design for a table top comprising two boards as shown and described.

DESCRIPTION

1. Table top comprising two boards
  - 1.1 is a right side view of a first component showing my new design separate for clarity of illustration.
  - 1.2 is a left side view thereof.
  - 1.3 is a rear view thereof.
  - 1.4 is a rear view of a second component shown separate for clarity of illustration.
  - 1.5 is a left side view thereof.
  - 1.6 is a right side view thereof.
  - 1.7 is a top view thereof.
  - 1.8 is a top view of the first component.
  - 1.9 is a bottom view of the second component.
  - 1.10 is a bottom view of the first component.
  - 1.11 is a front view of the second component.
  - 1.12 is a front view of the first component.
  - 1.13 is a front perspective view of the second component.
  - 1.14 is an enlarged view of detail A taken from view 1.13.
  - 1.15 is a rear perspective view of the second component.
  - 1.16 is an enlarged view of detail B taken from view 1.15.
  - 1.17 is a front perspective view showing both components assembled.
  - 1.18 is a rear perspective view thereof.
  - 1.19 is a front perspective view of the first component shown separately.
  - 1.20 is a rear perspective view thereof.
  - 1.21 is a front perspective view showing both components assembled in an environment of use.
- In the drawings, the broken lines illustrate environment that form no part of the claimed design.

1 Claim, 21 Drawing Sheets
